UNITED STATES PATENT OFFICE

160,600

REAR-VISION HAIR DRESSING MIRROR

Joseph A. Hill, Glen Ellyn, Ill., assignor to
George C. Schneider, Evanston, Ill.

Application May 3, 1950, Serial No. 9,687

Term of patent 7 years

(Cl. D57—1)

To all whom it may concern:

Be it known that I, Joseph A. Hill, a citizen of the United States, residing at Glen Ellyn, in the county of Du Page and State of Illinois, have invented a new, original, and ornamental Design for a Rear-Vision Hair Dressing Mirror, of which the following is a specification, reference being had to the accompanying drawing, forming a part thereof.

In the drawing:

Fig. 1 is a front perspective view of a rear vision hair dressing mirror, showing my new design; and

Fig. 2 is a rear perspective view thereof.

I claim:

The ornamental design for a rear-vision hair dressing mirror, substantially as shown.

JOSEPH A. HILL.
